MULTISTAGE CENTRIFUGAL COMPRESSOR

Ralph M. Watson, Bloomfield, N. J., assignor to
Worthington Pump and Machinery Corporation,
Harrison, N. J., a corporation of Delaware

Application November 15, 1946, Serial No. 710,070

11 Claims. (Cl. 230—130)

1

This invention relates to centrifugal compressors and an object of the present invention is to provide large turbo-compressors which embody maximum standardization of parts which will permit relatively low cost of manufacture and expedite delivery of such machines.

Most requirements for compressors of this type are individual to specific requirements, and it has been the practice heretofore to design, engineer and build each compressor to meet the particular requirements of its use, resulting in not only relatively high cost of manufacture but also in considerable time consumed in building and completing the compressor for delivery after receipt of the order for it.

An object of the present invention is to provide a centrifugal compressor for compressing compressible fluids which is composed of a series of separate casings, one for each stage of compression, which casings are mounted independently of each other and free of mechanical attachment to adjacent stage casings, and each of which stage casings is supported, independently of other stage casings making up the complete compressor, by a circular flange normal to the shaft axis. The flanges are supported by a common cylindrical housing surrounding all of the stage casings and serving both as a supporting frame and a fluid tight enclosure sealing the entire machine within it. Each of said casings includes a stage impeller, volute passages and a return passage for directing the fluid from one stage to the successive stage of the multi-stage compressor.

The separate mounting of the stage casings in the outer compressor housing provides a wide range of flexibility in assembling various numbers of stage units and of fixing pressures and capacities to meet the requirements of the particular installation in which a compressor is to be used, while permitting the units to be standardized for economical manufacture.

Another object of the present invention is the provision of a centrifugal compressor as specified wherein the separate mounting of the stage units will permit temperature expansion of each unit without interference with adjoining units or the development of temperature stresses in the machine.

Another object of the present invention is to provide a compressor as specified wherein the pressures within the housing are controlled by clearance spaces, defined by the unit stage casings and the housing, which clearance spaces are sealed one from another and are located between

2

the unit-stage casings on the suction side of each unit-stage casing and the discharge side of the preceding unit-stage casing. Each of these clearance spaces is open to the discharge pressure of the succeeding impeller, or somewhat less, so that the venting of the discharge pressure of each impeller into the surrounding clearance space within the housing insures that each unit-stage casing and diffuser is subjected to a pressure which progressively increases from the suction end of the compressor to the discharge end. The casing as a whole is therefore subjected to an average internal pressure intermediate between the suction pressure and discharge pressure of the entire compressor.

With these and other objects in view as may appear from the accompanying specification, the invention consists of various features of construction and combination of parts, which will be first described in connection with the accompanying drawings, showing a centrifugal compressor of a preferred form embodying the invention, and the features forming the invention will be specifically pointed out in the claims.

In the drawings:

Figure 1 is a side elevation of the improved centrifugal compressor.

Figure 2 is an end view of the improved centrifugal compressor.

Figure 3 is a longitudinal section through the compressor.

Figure 4 is a diagrammatic view showing the double volute diffusion passages of the unit stage sections.

Figure 5 is a cross section taken on the line 5—5—5 of Figure 4.

Figures 6 to 17 inclusive are detail sections showing the cross-sectional progression of the diffusion spaces and taken on the line 6—6 to 17—17 inclusive of Figure 4.

Referring more particularly to the drawings the improved centrifugal compressor includes a housing 1 which is cylindrical in shape, being of uniform diameter throughout its length. The housing 1 is split longitudinally in a horizontal plane normal to the axis of the housing. The upper half 2 and lower half 3 are connected by means of flanges 4 so that when the lower half 3 is anchored to a supporting base (not shown) by means of the anchoring feet 5, the upper half 2 may be removed without effecting any of the internal parts of the compressor, or the suction and discharge piping (not shown). The suction and discharge piping are connected to the suction nozzle 6 and discharge nozzle 7 respectively,

both of which are attached to the lower half 3 of the casing 1. The suction nozzle 6, and discharge nozzle 7 may however without departing from the spirit of the present invention be located on the housing in any other positions than those shown, as conditions of use and installation of the compressor may dictate.

Each of the stage units of the centrifugal compressor includes a unit stage casing 10 substantially cylindrical in shape and split in the medial line thereof to form two halves which when joined together form the casing providing passages enclosing an impeller 11 which communicates with twin volute diffuser passages 12 in turn communicating with a return passage 13 for conducting the fluid from the twin volute diffuser passages 12 back toward the axis of the unit-stage casing 10 and delivering the fluid into a suction inlet passage 14 of a subsequent stage of the multi-stage compressor.

The twin volute diffuser passages 12 expand radially, enlarge in cross sectional area from their inlets to their outlets into the passages 14, and each diffuser passage progressively widens axially as it passes circumferentially around the impeller 11, so that as cut by a meridian plane the diffuser passages are stepped in axial width on each convolution (as clearly shown in Figures 6 to 17 inclusive of the drawings).

The twin volute diffusion passages 12 develop from points 180° apart, thus balancing any side thrust tending to deflect the shaft 25. The diffuser passages 12 decelerate the flow velocity gradually and efficiently by maintaining continuous curvature of passage in the same direction without reversal.

The impellers 11 may be of any approved type, but are shown in the drawings as of the integrally cast shrouded type with backward curved vanes directing the discharging fluid at a relative velocity more nearly tangential than radial and oppositely to the direction of rotation of the impellers 11.

Each of the unit-stage casings 10 has an annular flange 15 formed upon its perimeter which is normal to the axis of the casing and engages in an annular groove 16 formed in the inner surface of the housing 1 to independently mount and support each unit-stage casing 10 within the housing 1 in proper relation to the adjacent unit-stage casings so as to form a complete operative multi-stage compressor as clearly shown in Figure 3 of the drawings. Each unit stage casing 10 is arranged so that its return passage 13 will discharge into the inlet passage 14 of the succeeding stage of the compressor, excepting only the final unit-stage casing. The return passage 13 of the final or discharge unit-stage casing delivers the fluid from its twin volute diffuser into the annular discharge space 17 of the compressor, which space 17 delivers the fluid to the discharge nozzle 7.

The unit-stage casings 10 being supported and mounted independently of each other in the cylindrical housing or shell 1 by means of the annular flanges 15 provide clearance spaces 18 between each pair of adjacent unit-stage casings. The clearance spaces 18 are sealed one from another by the annular flanges 15 and are located between the suction side wall of one casing and the discharge side wall of the preceding unit-stage casing 10. The clearance spaces 18 are open to the approximate discharge pressure of the impeller at the suction side of which

they are located as clearly shown in Figure 3 of the drawings, so that each unit-stage casing 10 except the first stage is subjected to a pressure difference corresponding to only one stage compression of the fluid; the first stage casing is subjected to a somewhat greater pressure difference.

The formation of the clearance spaces 18 as just described divides the interior of the housing 1 into a series of independent spaces in which the pressures progressively increase from suction pressure of the compressor at one end to discharge pressure at the other end.

The separate mounting of the unit-stage casings 10 in the housing 1 gives a wide range of flexibility in assembling various numbers of stage casings and of fixing pressures generated by the compressor and its capacity to suit the requirements of a particular installation, while permitting the units to be standardized for economical manufacture. That is, the separate mounting of the unit-stage casings permits these unit-stage casings to be manufactured in quantity lots and the various units to be assembled, from stock, into a multi-stage compressor to meet the requirements of the individual installation in which it is to be used.

All of the unit-stage casings 10 in their co-operative positions are enclosed in the housing 1 which is fluid tight being rendered so by the connection of the horizontally split cylindrical shell 21 and the suction head 19 and discharge head 20. The suction head 19 and the discharge head 20 are substantially conical in shape, as clearly shown in Figure 3 of the drawings and are attached to the ends of the horizontally split cylindrical shell 21 in any suitable manner such as by bolting as shown at 22.

The suction head 19 co-operates with the suction side of the unit-stage casing 10 forming the first stage of compression of the compressor to provide an annular suction passage 23 which opens into the suction inlet 14 of the first stage unit-stage casing 10.

The discharge end head 20 co-operates with the discharge side of the unit-stage casing 10 forming the last stage of compression of the compressor to provide the annular discharge passage 17 into which the return passage 13 of the last stage unit-stage casing discharges.

The pressure in any one of the clearance spaces 18 and in the annular inlet passage 23 and annular discharge passage 17 is uniform around the circumference of the housing 1 with no distorting effect tending to deflect the housing 1 or the unit-stage casing 10 out of round.

The impellers 11 are carried by a shaft 25. The shaft 25 is of relatively large diameter avoiding the need of internal bearings, without risk of lateral vibration. The bearings, indicated at 26, are exterior of the housing head covers 19 and 20, where they can be properly lubricated and cooled. The outboard bearing 26 is completely enclosed and the only opening where leakage might occur is at the inboard end of the shaft where a suitable labyrinth seal, indicated at 27, is provided. The pressure to which the seal 27 is exposed is the inlet pressure of the compressor.

The axial thrust of the shaft 25 is carried by a balancing drum 28 the outer side of which is exposed to inlet pressure of the compressor in the chamber or space 29 behind the balancing drum 28.

Fluid under inlet pressure of the compressor is delivered to the chamber or space 29 through a

longitudinal passage 30, which has communication with the annular suction space 23, and with a passage 31 in the head 20, which passage 31 leads to the chamber or space 29 as clearly shown in Figure 3 of the drawings.

In order to make the housing 1 cylindrical and of simple manufacture, the impellers 11 progressively increase somewhat in diameter from suction to discharge of the compressor. This leaves sufficient space around the suction impeller 11 to accommodate a diffuser passage required by the greater volume of flow at the suction end of the compressor and less space around the discharge impeller where the compressed fluid requires less space, with the spaces around the intermediate impellers decreasing towards the discharge impeller progressively in proportion to the volume reduction of the fluid as it is compressed in the successive stages. Moreover the inlet impeller 11 must be axially wider than subsequent impellers due to the larger volume of fluid flow and the wider spacing of its shroud rings leaves less support for the centrifugal loads on the vanes of the impeller. Hence the suction impeller is reduced in diameter to keep the stresses within permissible values.

If the compressor is to be used in a refrigeration installation, or in any other installation where it is desired to bleed fluid, under a pressure greater than the suction pressure of the compressor, into the compressor, bleed inlets, as shown at 34 may be provided which open into any one or more of the clearance spaces 18 to provide inter-stage bleeding into the compressor, or inter-stage bleeding out of the compressor in installations where it is desired to use fluid at pressures below the final discharge pressure of the compressor.

It will be understood that the invention is not to be limited to the specific construction or arrangement of parts shown, but that these may be widely modified within the invention defined by the claims.

What is claimed is:

1. In a multi-stage centrifugal compressor, a series of unit-stage casings each including an impeller, a diffusion passage, and a return passage for delivering fluid to the suction of the succeeding unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, said unit casings and flanges arranged to form a clearance space between the suction side wall of one unit-stage casing and the discharge side wall of the preceding unit-stage casing, said clearance spaces being sealed from each other by said flanges, a passage connecting the clearance spaces with the discharge of the next succeeding impeller whereby each unit-stage casing will be subjected to a relatively small pressure difference.

2. In a multi-stage centrifugal compressor, a series of unit-stage casings each including an impeller, a diffusion passage, and a return passage for delivering fluid to the suction of the successive unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, said unit casings and flanges arranged

to form a clearance space between the suction side wall of one unit-stage casing and the discharge side wall of the preceding unit-stage casing, said clearance spaces being sealed from each other by said flanges, a passage connecting the clearance spaces with the discharge of the next succeeding impeller whereby each unit-stage casing other than the first and last will be subjected to a pressure difference corresponding to the pressure difference of only one stage compression of the fluid compressed, said housing being split horizontally, said clearance spaces being annular.

3. In a multi-stage centrifugal compressor, a series of unit-stage casings each including an impeller, a diffusion passage, and a return passage for delivering fluid to the suction of the successive unit-stage casings, a housing enclosing all of said unit-stage casings, annular flanges on the perimeter of said unit-stage casings, said housing provided with grooves receiving said flanges for connecting each unit-stage casing to said housing independently of the other unit stage casings, said unit casings and flanges arranged to form a clearance space between the suction side wall of one unit-stage casing and the discharge side wall of the preceding unit-stage casing, said clearance spaces being sealed from each other by said flanges, a passage connecting the clearance spaces with the discharge of the next succeeding impeller whereby each unit-stage casing other than the first and last will be subjected to a pressure difference corresponding to the pressure difference of only one stage compression of the fluid compressed, the impellers of said unit-stage casings increasing in diameter to regulate the volumes occupied progressively by the impeller of the inlet unit-stage casing to the impeller of the outlet unit-stage casing of the compressor.

4. In a multi-stage centrifugal compressor, a series of unit-stage casings each including an impeller, a diffusion passage and a return passage for delivering fluid to the suction of the succeeding unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, said unit casings and flanges arranged to form a clearance space between the suction side wall of one unit-stage casing and the discharge side wall of the preceding unit-stage casing, said clearance spaces being sealed from each other by said flanges, a passage connecting the clearance spaces with the discharge of the next succeeding impeller whereby each unit-stage casing other than the first and last will be subjected to a pressure difference corresponding to the pressure difference of only one stage compression of the fluid compressed, the impellers of said unit-stage casings increasing in diameter and decreasing in axial width to regulate the volumes occupied progressively by the impeller of the inlet unit-stage casing to the impeller of the outlet unit-stage casing of the compressor.

5. In a multi-stage centrifugal compressor, a series of unit-stage casings each including an impeller, a diffusion passage, and a return passage for delivering fluid to the suction of the succeeding unit-stage casing, a housing enclosing all of said unit-stage casings, annular flanges on the perimeter of said unit-stage casings, said housing provided with grooves receiving said flanges

for connecting each unit-stage casing to said housing independently of the other unit stage casings, said unit casings and flanges arranged to form a clearance space between the suction side wall of one unit-stage casing and the discharge side wall of the preceding unit-stage casing, said clearance spaces being sealed from each other by said flanges, a passage connecting the clearance spaces with the discharge of the next succeeding impeller whereby each unit-stage casing other than the first and last will be subjected to a pressure difference corresponding to the pressure difference of only one stage compression of the fluid compressed, the impellers of said unit-stage casings decreasing in volumetric capacity progressively from the impeller of the inlet unit-stage casing to the impeller of the outlet-stage casing of the compressor.

6. In a multi-stage centrifugal compressor, a series of unit-stage casings each including an impeller, a diffusion passage, and a return passage for delivering fluid to the suction of the succeeding unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, said unit casings and flanges arranged to form a clearance space between the suction side wall of one unit-stage casing and the discharge side wall of the preceding unit-stage casing, said clearance spaces being sealed from each other by said flanges, a passage connecting the clearance spaces with the discharge of the next succeeding impeller whereby each unit-stage casing other than the first and last will be subjected to a pressure difference corresponding to the pressure difference of only one stage compression of the fluid compressed, the impellers of said unit-stage casings decreasing in volumetric capacity progressively from impeller of the inlet unit-stage casing to the impeller of the outlet-stage casing of the compressor, said housing being of uniform diameter throughout its length.

7. In a multi-stage centrifugal compressor, a series of unit-stage casings each including an impeller, a diffusion passage, and a return passage for delivering fluid to the suction of the succeeding unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, said unit casings and flanges arranged to form a clearance space between the suction side wall of one unit-stage casing and the discharge side wall of the preceding unit-stage casing, said clearance spaces being sealed from each other by said flanges, a passage connecting the clearance spaces with the discharge of the next succeeding impeller whereby each unit-stage casing except the first will be subjected to a pressure difference not exceeding the pressure difference of only one stage compression of the fluid compressed, the diffusion passage of each of said unit-stage casings being in the form of twin-volutes which expand radially and enlarge in cross-sectional area progressively as they extend circumferentially around the impeller of the unit-stage casing.

8. In a multi-stage centrifugal compressor, a series of unit-stage casings each including an

impeller, a diffusion passage and a return passage for delivering fluid to the suction of the succeeding unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, said unit casings and flanges arranged to form a clearance space between the suction side wall of one unit-stage casing and the discharge side wall of the preceding unit-stage casing, said clearance spaces being sealed from each other by said flanges, a passage connecting the clearance spaces with the discharge of the next succeeding impeller whereby each unit-stage casing except the first will be subjected to a pressure difference not exceeding the pressure difference of only one stage compression of the fluid compressed, the diffusion passage of each of said unit-stage casings being in the form of twin-volutes which expand radially and enlarge in cross-sectional area progressively as they extend circumferentially around the impeller of the unit-stage casing, the impellers of said unit-stage casings increasing in diameter to regulate the volumes occupied progressively by the impeller of the inlet unit-stage casing to the impeller of the outlet unit-stage casing of the compressor.

9. In a multi-stage centrifugal compressor, a series of unit-stage casings each including an impeller, a diffusion passage and a return passage for delivering fluid to the suction of the succeeding unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, the diffusion passage of each of said unit-stage casings being in the form of twin volutes which expand radially and enlarge in cross-sectional area progressively as they extend circumferentially around the impeller.

10. In a multi-stage centrifugal compressor, a series of unit-stage casings each including an impeller, a diffusion passage and a return passage for delivering fluid to the suction of the succeeding unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, the diffusion passage of each of said unit-stage casings being in the form of twin volutes which expand radially and enlarge in cross-sectional area progressively as they extend circumferentially around the impeller, the impellers of said unit-stage casings increasing in diameter to regulate the volumes occupied progressively by the impeller of the inlet unit-stage casing to the impeller of the outlet unit-stage casing of the compressor.

11. In a multi-stage centrifugal compressor, a series of unit-stage casings each including an impeller, a diffusion passage and a return passage for delivering fluid to the suction of the succeeding unit-stage casing, a housing enclosing all of said unit-stage casings, annular flanges on the perimeter of said unit-stage casings, said housing provided with grooves receiving said flanges for connecting each unit-stage casing to said housing independently of the other unit stage casings, the diffusion passage of each of said

unit-stage casings being in the form of twin volutes which expand radially and enlarge in cross-sectional area progressively as they extend circumferentially around the impeller, the impellers of said unit-stage casings increasing in diameter and decreasing in axial width to regulate the volumes occupied progressively by the impeller of the inlet unit-stage casing to the impeller of the outlet unit-stage casing of the compressor.
